UNITED STATES PATENT OFFICE.

JOSEPH E. TURNER, OF KANSAS CITY, MISSOURI.

SASH-LOCK.

1,178,557.

Specification of Letters Patent. Patented Apr. 11, 1916.

Application filed December 31, 1915. Serial No. 69,637.

To all whom it may concern:

Be it known that I, JOSEPH E. TURNER, a citizen of the United States, and a resident of Kansas City, in the county of Jackson and State of Missouri, have invented a certain new and useful Improvement in Sash-Locks, of which the following is a specification.

My invention relates to improvements in sash locks.

The object of my invention is to provide a sash lock of novel construction, which is economical to manufacture, not liable to get out of order and durable, and which is efficient for the purpose of drawing the two sashes of a window closely together, and to prevent unauthorized opening of the window from the outside.

The novel features of my invention are fully described and claimed hereinafter.

In the accompanying drawing, which illustrates the preferred embodiment of my invention, Figure 1 is a vertical sectional view of my improved sash lock shown applied to the sashes of a window. Fig. 2 is an elevation of the lower rail of the upper sash with the screw threaded plate for engaging the screw attached thereto. Fig. 3 is an elevation of the upper rail of the lower sash with the screw and the plate in which it slides mounted thereon.

Similar reference characters designate similar parts in the different views.

1 designates the lower rail of the upper sash, and 2 a plate attached by screws 3 to the forward side thereof. The plate 2 is provided with a screw threaded hole 4 adapted to have fitted removably therein the threaded outer end of a horizontal screw 5, which is provided at its forward end with a head 6 disposed forward or at the inner side of a plate 7, which is secured by screws 8 to the inner side of the upper rail 9 of the lower sash. The plate 7 is provided with a hole 10 in which the screw 5 is longitudinally movable. Preferably, the hole 10 is horizontally oblong so as to permit lateral movement therein of the screw 5 to accommodate the parts to any relatively lateral movement between the two sashes. To receive the screw 5, the rail 1 has a hole 4'.

The screw 5 is provided intermediate of the head 6 and the threaded end of the screw with a stop which, preferably, is longitudinally adjustable to accommodate the device to sashes of different thicknesses. In the drawing this stop is shown as being a collar 11, which is adapted to be fitted in either of two annular peripheral grooves 12. The collar is preferably a transversely divided ring of resilient material, such as spring wire, whereby the collar, if of slightly less internal diameter than the screw shank, will contract when fitted in either of the grooves 12, so as to be tightly clamped on the screw. The collar 11 is adapted to engage the plate 7, after the screw 5 has been withdrawn from the plate 2, for the purpose of limiting the outward movement of the screw.

In operating my invention, the parts having been attached to the sashes on which they are to be used, the sashes are moved to the closed position, shown in Fig. 1, in which position the screw 5 is adapted to enter the hole 4, when the screw has been moved to a position for engagement with the plate 2, and then turned in the proper direction. The head 6 bearing against the plate 7 will cause the screw on being properly turned to draw the rails 1 and 9 tightly together. By reversing this operation, and then withdrawing the screw 5 until the collar 11 strikes the plate 7, the two sashes will be released from each other. The screw cannot be released from the outside of the window, so that when engaged with the plate 2, unauthorized opening of the window cannot be effected without the glass of the sash being broken, or the stops of the window removed.

I do not limit my invention to the structure shown and described, as modifications, within the scope of the appended claim, may be made without departing from the spirit of my invention.

What I claim is:—

In a sash lock, a screw having at one end a head and screw-threaded at the other end and provided with a stop, a plate having means for attachment to the inner side of a sash rail and having a screw-threaded hole adapted to receive the threaded end of

said screw, and a plate adapted to be secured to the inner side of an opposing rail of another sash and having an oblong hole in which the screw is longitudinally slideable and laterally movable, the last named plate having its outer side adapted to serve as a bearing for said stop, when the screw

is in the unlocked position, and having its opposite side adapted to serve as a bearing for the head of the screw, when the latter is 10 in the locked position.

In testimony whereof I have signed my name to this specification.

JOSEPH E. TURNER.
